US00D800970S

(12) **United States Design Patent** (10) **Patent No.:** **US D800,970 S**
(45) **Date of Patent:** **** Oct. 24, 2017**

(54) **POULTRY CONTAINER FLOOR WITH WASTE APERTURES**

(71) Applicant: **LIFE-SCIENCE INNOVATIONS, LLC**, Willmar, MN (US)

(72) Inventors: **Richard Huisenga**, Willmar, MN (US); **Shawn Engstrom**, Willmar, MN (US)

(73) Assignee: **LIFE-SCIENCE INNOVATIONS, LLC**, Willmar, MN (US)

(**) Term: **15 Years**

(21) Appl. No.: **29/528,124**

(22) Filed: **May 26, 2015**

(51) **LOC (10) Cl. 30-02**

(52) **U.S. Cl.**

USPC **D30/120; D30/152**

(58) **Field of Classification Search**

USPC D30/108, 109, 113, 114, 115, 116, 117, D30/118, 119, 120; D25/152, 153, 154, D25/155, 156, 114, 115, 116, 117; D5/1, D5/2

CPC A01K 31/007

(57) **CLAIM**

The ornamental design for a poultry container floor with waste apertures, as shown and described.

DESCRIPTION

FIG. 1 is a top perspective view of a pattern of poultry container floor with waste apertures of the claimed design; FIG. 2 is a bottom perspective view of the design of FIG. 1; FIG. 3 is a top plan view of the design of FIG. 1; FIG. 4 is a bottom plan view of the design of FIG. 1; and, FIG. 5 is an enlarged cross-sectional view of one of the waste apertures taken along line 5-5 in FIG. 3. The dash-dot-dash broken line defines the limits of the claimed design.

1 Claim, 5 Drawing Sheets
